MECHANICALLY OPERATED DOOR CHIME ACTUATOR

John G. Jolly, Cincinnati, Ohio, assignor to NuTune,
Inc., Cincinnati, Ohio, a corporation of New York

Application May 31, 1957, Serial No. 46,431

Term of patent 14 years

(Cl. D72—1)

Fig. 1

Fig. 2

Fig. 3

Figure 1 is a front plan view of the mechanically operated door chime actuator showing my new design.

Figure 2 is a side elevational view thereof.

Figure 3 is a top plan view thereof.

The back of the actuator, not shown, is substantially plain.

I claim:

The ornamental design for a mechanically operated door chime actuator, substantially as shown and described.
